Primary Examiner — Patricia A Palasik*(74) Attorney, Agent, or Firm* — Birch, Stewart, Kolasch & Birch, LLP(57) **CLAIM**

The ornamental design for a sandmixer, as shown and described.

DESCRIPTION

FIG. 1 is a perspective view of the sandmixer;

FIG. 2 is a front view of the sandmixer;

FIG. 3 is a rear view of the sandmixer;

FIG. 4 is a left side view of the sandmixer;

FIG. 5 is a right side view of the sandmixer;

FIG. 6 is a top view of the sandmixer; and,

FIG. 7 is a bottom view of the sandmixer.

The broken lines in the drawings depict unclaimed environmental subject matter.

1 Claim, 7 Drawing Sheets(56)
